UNITED STATES PATENT OFFICE.

GEORGE T. ERNEST AND JOHN BARRY, OF WASHINGTON, DISTRICT OF COLUMBIA.

TRUNDLE TOY.

1,306,755.

Specification of Letters Patent. Patented June 17, 1919.

Application filed March 20, 1919. Serial No. 283,904.

To all whom it may concern:

Be it known that we, GEORGE T. ERNEST and JOHN BARRY, citizens of the United States, residing at Washington, District of Columbia, have invented certain new and useful Improvements in Trundle Toys, of which the following is a specification.

This invention relates to improvements in trundle toys.

10 An important object of the invention is to provide a toy of the above mentioned character having means whereby a tank and soldier or soldiers are caused to be advanced in a manner resembling the advance of the 15 same in making an attack in actual war conditions.

A further object of the invention is to provide a toy of the above-mentioned character, which is attractive in appearance, interesting in operation, and simple in construction.

Other objects and advantages of the invention will be apparent during the course of the following description.

In the accompanying drawings forming a 25 part of this specification and in which like numerals are employed to designate like parts throughout the same,

Figure 1 is a side elevation of a toy embodying our invention,

30 Fig. 2 is a plan view of the same,

Fig. 3 is a longitudinal sectional view taken on line 3—3 of Fig. 2, parts in elevation, and,

35 Fig. 4 is a side elevation of the apparatus in use.

In the drawings, wherein for the purpose of illustration is shown a preferred embodiment of our invention, the numeral 5 designates a longitudinal frame, including sides 40 6, spaced as shown, and connected at their rear ends with a handle 7. At their forward ends, the sides 6 have connection with a transverse axle 8, rotatable with relation thereto, and having wheels 9, rigidly secured to the ends thereof, these wheels being arranged upon the opposite sides of the longitudinal frame 5.

Arranged upon the opposite sides of the longitudinal frame 5 are walking beams 10, 50 pivotally connected with the outer sides of the wheels 9, near their peripheries, as shown at 11. We preferably attach flag-staffs 12 to the forward ends of the walking beams, the same projecting upwardly and carrying flags 13, preferably the American flag. The rear ends of the walking beams

10 are slideable within suitably large openings formed in transverse guides 14, rigidly secured to the handle 7, and arranged upon opposite sides thereof. Upstanding flag-staffs 15 are secured to the guides 14, and carry flags 16, preferably American flags.

Figures 17, representing soldiers in the act of charging are rigidly secured to the tops of the walking beams, and move with them. 65 The wheels 9 are rigidly secured to the axle 8, and the pivots 11 are so positioned that when one walking beam 10 is lowered, the other is in the raised position. This is the preferred practice, but the invention is not necessarily restricted to the same.

Rigidly secured to the axle 8 is a pulley 18, arranged between the sides 6, and engaged by a flexible endless belt 19, engaging a rear pulley 20. This rear pulley is arranged between the sides 6 and is rotatable upon a transverse shaft 21, secured thereto. Arranged between the sides 6, and secured thereto by pins 22, is an elevating member 23, having a rear inclined face 24, extending 80 upwardly toward the forward end of the machine and a forward inclined face 25 extending downwardly toward the forward end of the machine. Pairs of spaced depression elements 26 are carried by the sides 6, 85 and arranged near the opposite ends of the elevating and lowering member 23, such member being disposed between the pulleys 18 and 20. The depression elements 26 have openings 27, arranged therebetween, to permit of the passage of attaching elements 27', as shown.

The numeral 28 designates tanks, secured to the attaching elements 27' and connected thereby with the endless belt 19, and held 95 spaced therefrom. The tanks are so arranged with relation to the endless belt that one tank will pass above the member 23 while the other tank is passing beneath it, the tanks being thereby timed in travel with respect to the movement of the two sets of soldiers, so that one tank is moved upon the member 23 while a set of soldiers is elevated or advanced.

We prefer to arrange a cannon 29 upon 105 the handle 7, as shown.

In operation, the handle 7 is held in the hand of the user, and the device pushed along the ground with the wheels 9 in contact therewith, as indicated in Fig. 4. This 110 movement of the wheels causes the walking beams to move upwardly and forwardly,

whereby the sets of soldiers partake of forward and upward movements, closely simulating the actual charging movements of soldiers. As each set of soldiers is moved 6 upwardly and forwardly, a tank is passed upon the member 23, giving the impression of the tank going over irregular ground. This movement of the tank is timed with the movement of the set of soldiers, as above 10 indicated, whereby an interesting effect is produced, closely simulating a charge performed by a tank, serving to protect or cover the soldiers.

We prefer to paint the different parts of 15 the machine red, white and blue, thus the frame 5 may be painted blue, the wheels 9 red, and the walking beams 10 white. The soldiers may be painted any suitable color. The invention is in no sense restricted to the 20 idea of painting the different parts of the toy in any particular color.

It is to be understood that the form of 25 our invention herewith shown and described is to be taken as a preferred example of the same, and that various changes in the shape, size, and arrangement of parts may be resorted to without departing from the spirit of our invention or the scope of the subjoined claims.

30 Having thus described our invention, we claim:

1. A toy for simulating a tank charge in warfare, comprising a support, a wheel connected with the forward end of the support, 35 a tank carried by the support, means to cause the tank to travel longitudinally of the support, a plurality of soldiers, and means to advance the soldiers so that they move in proximity to the tank and in the same direc- 40 tion.

Copies of this patent may be obtained for five cents each, by addressing the "Commissioner of Patents, Washington, D. C."

2. A toy of the character described, comprising a support, a wheel connected with the forward end thereof, a walking beam having connection with the wheel and connected with the rear end of the support, a 45 plurality of soldiers carried by the walking beam, a tank to travel longitudinally of the support, and means to move the tank forwardly longitudinally of the support, such means being driven by the wheel and timed 50 with relation to the movement of the walking beam so that the soldiers are moved in proximity to the tank when the tank is moved to the advanced position.

3. A toy for simulating a tank charge in 55 warfare, a longitudinal frame, a transverse axle connected with the forward end thereof, wheels rigidly secured to the axle, walking beams connected with the wheels, guide means secured to the rear end of the longitudinal frame and engaging the walking beams, soldiers carried by the walking beams, a pulley carried by the transverse axle and driven thereby, a second pulley connected with the rear portion of the longitudinal frame, an endless belt engaging the pulleys, an elevating and lowering member arranged between the pulleys and engaged by the endless belt, and a plurality of tanks connected with the endless belt to be moved 60 thereby, said tanks being so located upon the endless belt that one tank is moved upon the elevating and lowering member as one set of soldiers is moved forwardly and upwardly 65 in proximity thereto. 75

In testimony whereof we affix our signatures.

GEORGE T. ERNEST.
JOHN BARRY.
